UNITED STATES PATENT OFFICE

2,682,621

GASEOUS DISCHARGE TUBE

Howard B. Sloan, Lynn, Mass., assignor to Sylvania Electric Products Inc., Salem, Mass., a corporation of Massachusetts

Application December 31, 1948, Serial No. 68,623

2 Claims. (Cl. 313—205)

1

This invention relates to electric gaseous discharge tubes in general and in particular to such devices having a cathode comprising a highly electron-emissive material.

The invention is especially directed to discharge tubes of this type for pulsed excitation.

An object of the invention is to prolong the life of such tubes and particularly to their cathodes.

Further objects are to reduce sputtering from the cathode and the consequent blackening of 10 the tube walls.

A feature of the invention is an insulating tube around the cathode. Another feature is an enlarged electrode chamber in the neighborhood of said cathode and a further feature is an insulating tube extending into said chamber toward said cathode and spaced from the first-mentioned insulating tube.

Other features, objects and advantages of the invention will be apparent from the following specification taken in connection with the accompanying drawings, in which:

Fig. 1 represents a profile view, partly cut away, of a tube according to the invention; and

Fig. 2 is a view, partly in section, of a cathode chamber according to a variation of the invention.

In Figure 1 the tubular glass envelope 1 has the anode wire 2, preferably of tantalum, sealed through one end. The enlarged electrode chamber 3 is sealed to the other end and the lead-in wire 4 sealed through the end of said chamber 3. The tantalum cathode strips 5 constituting a "cold" type of cathode, lacking a heater, is welded or otherwise attached to diametrically opposite parts of the lead-in wire 4 near the inner ends thereof. These strips may be bent toward each other above the inner end 8 of lead-in wire 4 and may be welded or otherwise fastened together where they meet, for example at the intermediate portions 9, and be afterward flared outward from each other at their free ends 6 and 7. The flared free ends 6, 7, may be coated, for example, with a mixture of barium, strontium and calcium carbonates or nitrates, common in the art, preferably with the addition of a small amount of nickel nitrate. This cathode structure 5 may be enclosed in a glass tube or inert sleeve 10 concentric therewith and ending near the free end of the cathode 5. Another glass tube 11 preferably of slightly larger diameter extends into the electrode chamber 3 from the tube 1 toward the cathode 5 and terminates a short distance away from the tube 10 which therefore does not open freely into chamber 3 but, instead, tube 10 communicates with chamber 3 through a constricted

2

passage. The tube may be coiled to have several turns 12, 13, if desired. The tube may be filled with an inert gas, for example xenon at a pressure which may be for example, 75 mm. of mercury.

In Fig. 1, the tube 11 is spaced longitudinally from tube 10. Figure 2 shows an arrangement where tube 11 extends beyond the end of tube 10, but is spaced radially therefrom.

In operation the lead-in wires 4 and 14 may be connected across a suitable source of voltage, generally of a highly pulsed type, for example, across a condenser. If desired, a starting wire 15 may be wrapped around suitable portions of the tube 1, as shown for example in copending application Serial No. 18,254 filed March 31, 1948, by Harold Heins and Donald Coggins. This device is very suitable for airport approach lighting systems such as that there shown. The use of 15 the insulating tubes 10 and 11 has been found to greatly increase the life of tubes of this nature and at the same time to make a tremendous decrease in the blackening of the tube particularly in the neighborhood of the cathode 5. Apparently this is due to the building up of a pressure 20 in tube 1 during the discharge, this pressure forcing gas out into the main electrode chamber 3 through the constricted space between the ends of tubes 10 and 11, the pressure in electrode chamber 3 remaining low. However I do not 25 wish to be bound by this theory for the mechanism of my invention is still somewhat obscure, although the results obtained are quite definite. The tubes 10 and 11 may be used with other types 30 of cathode without departing from the spirit of the invention and I have found the type of cathode described to be especially useful.

Other transparent insulating materials for example quartz may be used instead of glass in a device according to my invention; the word glass being used in my specification and claims in a generic sense to include such materials.

What I claim is:

1. An electric discharge lamp comprising an 45 enclosing envelope having a coiled light-emitting portion and containing a gas, an anode at one end thereof, and a cathode at the other, said envelope having an enlarged chamber at the end near the cathode, a reentrant tube extending and communicating from the light-emitting portion into said chamber toward said cathode, and another tube open toward but spaced from said reentrant tube and enclosing said cathode except for this opening.

2. An electric discharge lamp comprising an

enclosing envelope having a coiled light-emitting portion and containing a gas, an anode at one end thereof, and a cathode at the other, said envelope having an enlarged chamber at the end near the cathode, a reentrant tube extending 5 and communicating from the light-emitting portion into said chamber toward said cathode, and another tube spaced longitudinally from said reentrant tube and otherwise surrounding said cathode but spaced therefrom.
